United States Patent Office.

HARRIET A. HUMPHREY, OF MILWAUKEE, WISCONSIN.

Design No. 4,088, dated May 31, 1870.

DESIGN FOR HAIR-CRIMPERS.

The Schedule referred to in these Letters Patent and making part of the same.

I, HARRIET A. HUMPHREY, of Milwaukee, in the county of Milwaukee and State of Wisconsin, have invented and produced a new and original Design for a Hair-Crimper.

Its object is to crimp the hair without heat, or breaking the hair; and I hereby declare that the following is a full, clear, and exact description, reference being had to the accompanying drawings making a part of this specification, in which—

Figure 1 is a perspective view, when closed.

Figure 2 is the same, when opened.

In the drawings—

A is a number of rods, held together by two metallic pins, B and C. B is stationary, it being headed at both ends. C is entirely withdrawn when the crimper is to be opened, and alternate rods, 1 3 5 7, are raised, to admit the moistened hair, and, when

closed, C is replaced and secured by elastic band D, holding the hair in a crimped position, and the device is to be worn until the hair is dry.

Said rods are to be made of hard rubber, wood, horn, or any other light material of which they can be made, and of any size and length desired, and slightly curved to fit the head.

Claim.

What I claim as new, and desire to secure by Letters Patent, is—

The design for a hair-crimper, as described and shown.

HARRIET A. HUMPHREY.
